(57) **CLAIM**

We claim the ornamental design for a kitchen aerator, as shown and described.

DESCRIPTION

FIG. 1 is a right side perspective view of a kitchen aerator in accordance with the present invention;

FIG. 2 is a front elevational view of the kitchen aerator in accordance with the present invention;

FIG. 3 is a rear elevational view of the kitchen aerator in accordance with the present invention; and,

FIG. 4 is a left side elevational view of the kitchen aerator in accordance with the present invention, the right side elevational view being the mirror image thereof.
